UNITED STATES PATENT OFFICE

STANLEY H. HOBSON, OF ROCKFORD, ILLINOIS, ASSIGNOR TO GEO. D. ROPER CORPORATION, OF ROCKFORD, ILLINOIS, A CORPORATION OF ILLINOIS

GAS RANGE

Application filed May 21, 1927. Serial No. 193,276.

This invention relates to gas ranges and is more particularly devoted to an improved closed top stove so designed and constructed that the use of four or more burners, in front and rear sets, is rendered thoroughly practical, and about the same operating efficiency is secured as with an ordinary open top stove.

Actual test has shown that if the open top on a gas stove is replaced by a closed top without any further alterations there will be evidence of very bad "floating", showing that combustion is incomplete. This is due to the fact that the products of combustion are not conducted away from the burners and prevent secondary air from reaching the flame. According to the present invention I, therefore, employ a distributor plate placed between the burners and the closed top and having connection at the back of the stove with an outlet flue. The distributor plate has openings therein over the several burners and conforming to the shape thereof. The flame protrudes through these openings and induces a flow of secondary air upwardly about the burners and through the openings. The openings are made sufficiently large so as not to give rise to any trouble in case the burners do not register precisely with the openings. Furthermore, the openings are defined by upturned flanges which serve in the nature of flues to further induce the upflow of secondary air through the openings. The upturned flanges also serve to segregate the products of combustion above the distributor plate from the incoming secondary air to prevent contamination of the latter. In other words, the upturned flanges perform a double function; they serve to induce a good draft of secondary air to the flame and also prevent contamination of the air by the products of combustion. In fact, the isolation of the products of combustion is so complete that there is never any evidence of faulty operation of the rear burners when the front burners are in use or vice versa.

Experiments on the present stove have also shown that the distance between the distributor plate and the top should be not less than an inch and a half in order to afford an ample chamber for the products of combustion.

They also showed that the distance from the cooking top to the burner should be not less than an inch and seven-eighths for efficient operation. According to the present invention I have, therefore, provided the distributor plate with raised portions at each of the burners wherein the burner openings are provided, the raised portions permitting the proper disposition of the burners and of the distributor plate without placing any undue restriction upon the passage of secondary air between the burners and the distributor plate to reach the flame. In this way, floating of the flame is avoided and the desired efficiency is secured.

Experiments further showed that ordinary burners, such as are used in open top stoves, are unsuited for the present purpose as they give very low efficiency when dropped to the level herein required. According to the present invention I have provided a specially designed burner giving the desired flame buildup and have so disposed the ports therein for easy access thereto by the secondary air, the innermost parts, which tend to be starved to such an extent that floating of the flame jets therefrom is quite noticeable, being insured of the proper draft of secondary air by a unique arrangement of auxiliary ports. These burners, when operated in connection with a distributor plate constructed as hereinabove briefly set forth, operate without any evidence of floating and at a very high efficiency at all loads from the lowest to the highest.

The invention is described in greater detail hereinafter by reference to the accompanying drawings in which—

Figure 1 is a plan view of the cooking top of a gas stove made in accordance with my invention, the left hand half of the closed top being removed to disclose the distributor plate therebeneath, through the openings of which the burners are visible, and one of the lids in the right hand half being removed to disclose the grate provided in the opening;

Fig. 2 is a longitudinal vertical section taken on the line 2—2 of Fig. 1 looking in the direction of the arrows; and

Figs. 3, 4 and 5 are enlarged sectional de-

tails taken on the three section lines shown in Fig. 1 looking in the directions indicated, these views serving to illustrate the novel construction of the burner itself and also the co-operation of the distributor plate therewith, the formation of the openings in the latter being clearly shown in these views.

The same reference numerals are applied to corresponding parts throughout the views.

10. The cooking top, indicated generally by the reference numeral 6, in the case of a gas range of the cabinet type will, of course, have the usual oven section at either side thereof. The same has not been illustrated inasmuch as the invention is not limited to any particular type of range. In the cabinet type, however, a back splasher wall 7 and a burner box back 8, together with a drip pan 9, and the usual manifold pipe 10 are provided in conjunction 15 with the cooking top. These appurtenances are shown more or less fragmentarily. The cooking top is of the closed type and has top plates 11 set in the rabbeted portions 12 thereof, as shown, so as to present a smooth, flat 20 top surface. The top plate has openings 13 closed by lids 14, the number of openings depending upon the number of burners employed. The latter are indicated at 15. In the present case four burners are shown, two 25 in a front set and two in a rear set. The manifolds 16 of the burners extend forwardly for connection with the manifold pipe 10 in the usual manner. The manifolds for the front burners are made straight, as indicated in 30 Fig. 1, while those of the rear burners are curved to permit the disposition of the rear burners in line with the front burners in the usual way. A distributor plate 17 is fastened 35 on the under side of the cooking top 6 between the top plate 11 and the burners 15 and thus provides a combustion chamber at 18. A secondary air chamber is provided at 19 between the drip pan 9 and the distributor plate 17.
40. The plate 17 is provided with openings 20 at the several burners, these openings being star-shaped to correspond to the shape of the burners 15 and serving to restrict the supply of secondary air to a confined continuous 45 area around the flames of each burner. By reason of these openings sufficient secondary air will be entrained by the flames and the natural draft produced by the rising heated air and the expanding products of combustion 50 to support complete combustion of the gas mixture delivered from the burners. The provision of the openings of such size and shape insures proper operation despite a failure to get the burners in precise registration 55 therewith. From the point of view of assembling this is obviously of considerable importance. The wall of each opening 20 is formed by an upstanding flange 21 further defining the confined continuous area around the flames of each burner which serves to im-

prove the entrainment of secondary air. These flanges are beneficial for all of the burners but are essential only for the rear burners because here they serve a further and important function namely that of segregating the products of combustion in the combustion chamber 18 from the incoming secondary air. Contamination of the secondary air is thereby prevented and, as a result, there is no evidence of floating inasmuch as combustion is bound to be complete. The isolation of the products of combustion is so complete that there is never any evidence of contamination of the secondary air at the rear burners when the front burners are in use, or vice versa, as was frequently the case in previous designs with which I am familiar. As a matter of fact, previous designs have not succeeded in overcoming this difficulty to a practical extent. I have found that it is preferable to incline the flanges 21 inwardly toward parallelism with the inclined sides of the fingers of the burners in the manner most clearly illustrated in Fig. 5. This seems to cause the secondary air to impinge better upon the flame and makes for greater uniformity in the passage of air about the burners and through the openings in the distributor plate. I have also found it desirable to provide the openings 20 in raised portions 22 on the plate 17. The reason for this is that experiment with the present stove has shown that the proper distance between the distributor plate and the top plate should be not less than an inch and a half in order to afford an ample combustion chamber and the burner was found to operate most efficiently when disposed at not less than an inch and seven eighths from the top plate. This left too little clearance between the distributor plate and the burners for the proper passage of secondary air about the burners and into the combustion chamber. I avoid this difficulty by the provision of the raised portions, which permit the proper disposition of the burners and likewise the proper disposition of the distributor plate. The all-around efficiency is accordingly increased. The distributor plate has an opening 23 at the rear end thereof leading into a flue 24 for conducting the products of combustion from the chamber 18 and brackets 25 and 26 are affixed to the under side of the plate for the support of the front and rear burners, the brackets 25 providing a ledge on one side thereof to support a front burner and another ledge on the other side thereof to support a rear burner, as indicated in Fig. 20.

55. The burners 15, as stated above, are specially designed for the present purposes. The heads thereof are star-shaped, as shown, to provide fingers or branches 27 radiating from a center hole 28. The fingers 27 are drilled to provide main ports 29 in the top thereof in radially spaced relation, the open-

ings being sufficiently fewer in number and of sufficiently larger size as compared with the ports in an ordinary burner, such as is used in an open top stove, that the desired 5 flame build-up is secured to permit the lower disposition of the burner with respect to the cooking top is required in the case of a closed top stove. It will be observed that alternate fingers are provided with three ports while 10 intermediate ones are provided with two ports. There is, ordinarily, no difficulty in feeding an adequate supply of secondary air about the fingers of the burner to the two outermost ports on the fingers. The third or 15 innermost ports, however, were found to be hard to reach with secondary air and were starved to such an extent that there was considerable evidence of floating especially at the higher loads. I, therefore, provide auxiliary ports 30 in circumferentially spaced relation about the center hole 28, each of said ports being disposed between the inner ends of two adjacent fingers and directed at an acute angle with reference to the top of the 25 burner, the angle being approximately 60°, as clearly indicated in Fig. 4. The jets from these auxiliary ports, which, by the way, are of an appreciably smaller size than the main ports so as not to build up too large a flame 30 at the center of the burner, project upwardly and inwardly toward each other substantially as shown in Figs. 3 and 4, thus inducing a cross-draft between the fingers to feed the innermost ports and also an up-draft through 35 the center hole to further feed the said ports. The cross-draft and the central up-draft are clearly indicated by the arrows in Fig. 4. With this unique arrangement of auxiliary ports in conjunction with the main ports the 40 innermost ports are fed with secondary air to the same extent as the outermost ports at all loads and there is never any evidence of floating. The efficiency of the burner is, therefore, raised an appreciable degree. 45 It will be observed that the openings 13 in the top plate 11 have grates provided therein, as indicated at 31 in Fig. 1. The fingers of these grates extend radially, as shown, and are disposed between the fingers of the star-shaped burners. This avoids the likelihood 50 of the flame striking the grate and also enables the full flame to reach the cooking vessel. The radiating fingers of the grate are preferably cast integral with the top plate 55 for simplicity and economy.

I claim:

A gas range having, in combination, a Bunsen burner beneath the cooking top in such proximity thereto as to secure efficient 60 heating of a vessel supported thereon directly over the burner, a bottom plate interposed between the burner and the cooking top and forming with the latter a confined chamber through which the products of combustion 65 from the burner pass to a flue outlet, said

burner having a central secondary air passage and radiating fingers each of which has main flame ports in the top thereof in radially spaced relation, said plate having a single secondary air opening conforming to the arrangement of said flame ports in the burner, and a plurality of auxiliary flame ports in the burner wall arranged around said central secondary air passage near the top thereof and located between the inner ends of the radiating fingers and inclined inwardly and upwardly for projecting flame jets at such an angle with reference to the plane of the top of the burner as to serve in drawing air currents to the innermost flame ports in the top 75 of the burner.

In witness of the foregoing I affix my signature.

STANLEY H. HOBSON.
